UNITED STATES PATENT OFFICE.

JOSEPH ALEXANDER WILSON, OF HOOD RIVER, OREGON.

SCHOOL-DESK.

SPECIFICATION forming part of Letters Patent No. 340,847, dated April 27, 1886.

Application filed August 4, 1885. Serial No. 173,491. (No model.)

To all whom it may concern:

Be it known that I, JOSEPH ALEXANDER WILSON, of Hood River, in the county of Wasco and State of Oregon, have invented a new and 5 useful Improvement in School-Desks, of which the following is a description.

My invention is an improvement in the special class of school and other desks having covers which may be raised and secured at any 10 desired angle to their original position, for the purpose of adapting them for more convenient use in reading, writing, drawing, &c.

The improvement pertains to the construction and combination of parts employed for 15 holding the cover raised, and to devices for clamping a book or drawing, &c., thereto, as hereinafter described and claimed.

The accompanying drawing represents a perspective view of a school-desk provided with 20 my improvement.

The iron sides A are extended backward, as shown at g, and connected at that point by a narrow wooden cross piece or strip, a. The cover or lid B is attached by hinges e to this 25 part a. To the under side of the cover B, and near its free edge, is attached a bar, C, which is curved eccentrically to the hinge-point f, and (when the cover is down) projects through a slot in the bottom of the desk. It is apparent 30 that if the said bar were curved concentrically its free end would project farther below the desk, (when the cover is closed,) and thus unduly obstruct the space beneath it, which should be as open as possible to permit free 35 movement of the pupil's legs and feet.

To the bottom and front of the desk are secured the respective ends of a right-angular bar, D, whose horizontal portion is slotted, as

shown. A clamp-screw, E, passes through the slots of both bars C D. When loosened, it allows the cover B to be raised and lowered without hinderance; but when tightened it clamps the movable bar C firmly to the fixed bar D, and thereby holds the cover supported at the required angle for convenient use in reading or writing, &c.

The screw E obviously moves upward or downward in the slot of curved bar C and along the horizontal slot of bar D whenever the cover is adjusted.

To hold a book open on the cover B, I use clamps f, which pass through holes in the latter, and have spiral springs applied to their shanks. The springs press downward against the nuts on the extremities of the clamps and upward against the under side of the cover. The upper ends of the clamps f are bent at a right angle, and lie flush in grooves formed in the cover when the clamps are not in use.

What I claim is—

1. In a desk, the combination, with the hinged cover, of the curved slotted bar attached to its under side, the fixed bar secured to the body of the desk and having a slot in its horizontal portion, and a clamp-screw working in the slots of both bars, as shown and described, for the purpose specified.

2. The combination, with a book-support, of angular clamps which pass through the latter and springs applied to their shanks on the inner side of the support, substantially as shown and described.

JOSEPH ALEXANDER WILSON.
